UNITED STATES PATENT OFFICE.

CLYDE S. WRIGHT, OF TOLEDO, OHIO, ASSIGNOR TO THE NATIONAL SUPPLY COMPANY, OF TOLEDO, OHIO, A CORPORATION OF OHIO.

JACK.

1,309,973.

Specification of Letters Patent. Patented July 15, 1919.

Application filed October 19, 1918. Serial No. 258,894.

To all whom it may concern:

Be it known that I, CLYDE S. WRIGHT, a citizen of the United States, residing at Toledo, in the county of Lucas and State 5 of Ohio, have invented new and useful Improvements in Jacks, of which the following is a specification.

My invention relates to jacks and more particularly to that type thereof known as 10 the Barrett type of jacks, as exemplified in Barrett's Patent No. 527,102, granted October 9, 1894.

It is the principal object of the present invention to reduce the number of parts 15 employed in the jack of the said patent and to otherwise simplify the same and reduce the cost thereof.

The accompanying drawings, Figures 1 to 5, inclusive show a side elevation of my 20 invention with the cover-plate removed and with the ends of the operating handle and the rack broken off, the several views showing the operating parts in the successive 25 positions they assume in the operation of the jack.

On the drawings 1 is a carriage adapted 30 to travel on the rack 2 by the reciprocation of the operating lever 3 having fulcrum or bearing pins journaled in the carriage, only one bearing 4 being shown.

The lever 3 carries within the carriage two pawls 5 and 6 arranged on opposite sides of the pin 4 so that, as the lever is reciprocated, one pawl will move forwardly and 35 the other backwardly. The pawls are adapted to engage with the teeth on the top of the rack and, when not prevented from free operation by the links 7 and 8, will cause the carriage to travel in the direction of the arrow D against a force applied 40 against the carriage and in the direction of the arrow R, as will be readily understood.

Within the rear portion of the carriage 45 I place the reversing lever 9 which is pivoted between its ends on the pin or pivot 10, the lower end of this lever being just in front of the opening 11 in the lower part of the rear end of the carriage and its upper end lying preferably somewhat above the level of the pin 4. 12 is a trip lever pivoted on the pivot 13 and arranged so 50 that its lower end may be swung up through the opening 11 and in contact with the rear face of the lower end of the reversing lever

9 so as to move the latter from the position shown on Fig. 1 to that shown on the other figures, and lock the same in the latter position, in a manner well known in the art. The upper end of the lever 9 is provided 60 with the center pin 14, around which is coiled the center of the spring 15 having the upper and lower members 16 and 17 pivotally connected to the respective links 7 and 8. These links have the slots 18 and 19 65 by means of which there exists some lost motion between the links and the pawls connected together by the headed pivots or pins 20 and 21 passed through the respective slots 18 and 19 and entering the pawls 5 and 6, 70 respectively.

22 is a stop-lug on the lever 9 at the rear of the spring member 17 for limiting the rearward movement of the said member. The rearward movement of the spring member 75 16 is limited by the stop-lug 23 on the carriage.

On Figs. 2 to 5, as on Fig. 1, the arrows R indicate the place and direction of the resistance to the jack, and the arrows D the 80 direction of movement of the jack.

Assuming that there is a left-hand pressure against the carriage as indicated by the arrow R and that the parts of the jack are as shown on Fig. 1, the carriage may 85 be moved toward the left as follows: The lever 12 is swung from the upright position shown on Fig. 1 to the horizontal position shown on Fig. 2, whereby the lever 9 becomes locked with its upper end in its rear 90 position and the links 7 and 8 are moved to the left so that the pivots 20 and 21 lie in the right-hand ends of the slots 18 and 19, and cause the spring members to be put under tension tending to draw the links 95 to the left and the pawls out of engagement with the rack 2, the pressure to the left on the carriage, however, holding the pawls firmly in the teeth of the rack.

The parts being now as shown on Fig. 2, 100 the lever 3 is moved slightly to the left which causes the pawl 6 to move the carriage slightly to the right and the pawl 5 slightly in the same direction, which releases the pawl 5 from the rack. The spring member 105 16, being under strain, at once draws this pawl up above the rack. The lever 3 is then moved to the right which allows the carriage to move to the left. At the same time the lever 3 moves the pawl 5 to the left. The 110

pawl 5 owing to the movements of the carriage and the lever 3 rides to the left above the top of the tooth from which it was just released. The position of the parts at the 5 moment of the release of the pawl 5 is shown on Fig. 3, where the lug 24 on the lever 3 engages the top of the pawl 5 and prevents its engagement with the pawl 6. Soon the spring members 16 and 17 are both in engagement with their stops and the pivot 20 rides to the left in the slot 18, which allows the pawl 5 to drop in front of and engage the next tooth on the rack, as shown on Fig. 4. During the movement of the carriage to 10 the left by the right-hand movement of the lever 3 the pawl 5 was traveling to the left with the carriage and the lower end of the lever 3. As the carriage moves to the left the pawl 6 being stationary, the member 17 15 of the spring 15 is placed under tension since the pivot 21 is at the right end of the slot 19, thereby holding the lower end of the member 17 at a fixed position.

By moving the lever 3 in Fig. 4 slightly to 20 the right, the pawl 5 moves the carriage slightly to the right which releases the pawl 6 from the rack, whereupon the spring-member 17 draws the pawl 6 above the rack as shown on Fig. 5. The handle is then 25 moved to the left which allows the carriage to move to the left and causes the pawl 6 to pass above the tooth from which it was just released. As the carriage travels to the left the spring-member 17 soon engages its stop 30 35 22, and the pawl 6 then moves down into engagement with the next tooth on the rack, when the parts are again as they were in Fig. 2 with the spring-member 16 under tension, ready to lift the pawl 5 when released as hereinbefore described.

I claim—

1. In a jack, a rack, a carriage adapted to travel thereon, an operating lever mounted on the carriage, two pawls carried by the 45 lever on opposite sides of its fulcrum, a one-part reversing lever carried by the carriage, means for locking it in a stationary position, a spring mounted directly on the reversing lever and having two spring-members, and 50 links connecting the spring members respectively to the pawls, there being a lost motion connection between the spring-members and the pawls to put one or the other of said spring-members under tension when the carriage is moved backwardly and to move the pawl away from the rack when released therefrom, and stops for limiting the movement of the spring-members in obedience to 55 their tensions.

pawl away from the rack when released therefrom.

2. In a jack, a rack, a carriage adapted to travel thereon, an operating lever mounted on the carriage, two pawls carried by the 60 lever on opposite sides of its fulcrum, an integral reversing lever carried by the carriage, means for locking it in a stationary position, a spring mounted directly on the reversing lever and having two spring-members, and links connecting the spring members respectively to the pawls, there being a lost motion connection between the spring-members and the pawls to put one or the other of said spring-members under tension 65 when the carriage is moved backwardly and to move the pawl away from the rack when released therefrom.

3. In a jack, a rack, a carriage adapted to travel thereon, an operating lever mounted on the carriage, two pawls carried by the 70 lever on opposite sides of its fulcrum, an integral reversing lever carried by the carriage and having a pin thereon, means for locking it in a stationary position, a spring 75 mounted on the said pin and having two spring-members, and links connecting the spring-members respectively to the pawls, there being a lost motion connection between the spring-members and the pawls to put one or the other of said spring-members under tension 80 when the carriage is moved backwardly and to move the pawl away from the rack when released therefrom.

4. In a jack, a rack, a carriage adapted to travel thereon, an operating lever mounted on the carriage, two pawls carried by the 85 lever on opposite sides of its fulcrum, an integral reversing lever carried by the carriage, means for locking it in a stationary 90 position, a spring mounted directly on the reversing lever and having two spring-members, links connecting the spring-members respectively to the pawls, there being a lost motion connection between the spring-members and the pawls to put one or the other of said spring-members under tension when the carriage is moved backwardly and to move the pawl away from the rack when released 95 therefrom, and stops for limiting the movement of the spring-members in obedience to their tensions.

Signed at Toledo, Ohio, this 14th day of October, 1918.

CLYDE S. WRIGHT.
